UNITED STATES PATENT OFFICE.

FRANCIS A. BARKER, OF SANTA MONICA, CALIFORNIA.

RADIATOR.

Application filed October 30, 1923, Serial No. 671,818. Renewed December 13, 1926.

This invention relates to water radiators for the cooling systems of internal combustion engines and has particular reference to an improved filling spout and closure cap therefor particularly adapted for use upon such radiators.

It is well known that for many reasons an internal combustion engine such as is commonly used in motor vehicles, will overheat or become excessively hot so as to cause boiling of the water in the cooling system of said engine. When this boiling of the water takes place, considerable danger is presented, such as bursting of the closure 10 cap of the filling spout of the radiator and its forcible projection from the spout, and, should the cap of the filling spout be removed at this time, the person removing the same is subject to being severely burned by 15 the escaping steam and boiling water.

The primary object of the present invention, therefore, is to provide a filling spout and closure cap therefor, through which the use of which the radiator will be sufficiently 20 vented to permit escape of steam therefrom, so that when the cap is removed from the filling spout, the person removing the same will not be subject to being burnt by the 25 boiling water, and whereby destruction of the cap is effectively prevented.

Another object of the invention is to provide means for regulating the escape of heat from the radiator or entrance of cold air thereinto, so that the device will not interfere 30 with the operation of the engine during cold weather.

Other objects will appear as the nature of the invention is better understood, and the same consists in the novel form, combination, 35 and arrangement of parts, hereinafter more fully described, shown in the accompanying drawings, and claimed.

In the drawing, wherein like reference characters indicate corresponding parts 40 throughout the two views:

Figure 1 is a fragmentary top plan view showing a radiator equipped with the filling spout and closure cap constructed in accordance with the present invention, and

Figure 2 is a substantially central vertical sectional view, of the device shown in Figure 1.

Referring more in detail to the drawing, 5 indicates the upper portion of the ordinary form of water radiator, employed in the cooling systems of internal combustion engines, and this radiator has a central opening in the top wall thereof, into which is threaded the lower end of a cylindrical filling spout 6. The filling spout 6 preferably consists of a tube having the ends thereof open and provided with an external annular flange 7 adapted to contact with the upper surface of the top wall of the radiator for limiting movement of the same into the opening of the radiator when the device is applied to the latter.

Threaded onto the upper end of a filling tube 6 is a screw cap 8 that is internally threaded and has its top wall provided with numerous relatively large perforations or openings 9 through which the steam and excessive heat may pass to the atmosphere from the radiator.

Arranged centrally within the filling tube 75 or spout 6 is a damper 10 mounted upon a transverse shaft 11 that is journaled in opposite sides of the filling tube and has a knob or handle 12 upon one end thereof for facilitating manual adjustment of said 80 damper.

The position of the damper will control the amount of steam or heat allowed to escape from the radiator and its position will be governed by the particular requirements 85 of each case with respect to the degree of overheating experienced and the temperature in the locality where the device is being used.

From the foregoing description, it is believed that the construction and operation 90 as well as the advantages of the invention will be readily understood and appreciated by those skilled in the art.

Minor changes may be made without departing from the spirit and scope of the invention as claimed.

What I claim as new is:

A radiator filling spout comprising a tubular open ended body externally screw threaded at its opposite ends and provided 100 adjacent but upward of its lower threaded end with an annular flange forming a stop shoulder, the lower threaded end being adapted to be tapped into an opening in the

radiator, and the flange being adapted to abut the latter, a perforated and screw threaded cap screwed onto the upper threaded end of said body, a shaft disposed transversely across the body at a point between the screw threaded ends, said shaft being journaled in one side wall of the body and having screw threaded connection with the

opposite side wall of the body, and a circular damper carried by the intermediate portion of the said shaft and disposed in the body. 10

In testimony whereof I affix my signature.

F. A. BARKER.
